United States Patent

Des. 236,113
Patented July 29, 1975

236,113

FOLDING PEN STAND

James G. Moore, Cedar Rapids, and Fay W. Oltman,
Anamosa, Iowa, assignors to Souvenir, Inc., Cedar Rapids, Iowa

Filed Jan. 2, 1974, Ser. No. 429,876

Term of patent 14 years

Int. Cl. D19—02

U.S. Cl. D19—84

FIG. 2

FIG. 1

FIG. 3

FIG. 4

FIG. 5

FIG. 1 is a top plan view of a folding pen stand in its flat condition showing our new design;

FIG. 2 is a left side elevational view;

FIG. 3 is a front elevational view;

FIG. 4 is a bottom plan view; and

FIG. 5 is a perspective view of the folding pen stand shown in an unfolded and operative condition.

We claim:

The ornamental design for a folding pen stand, substantially as shown and described.
